UNITED STATES PATENT OFFICE.

ALFRED A. ROY, OF LOWELL, MASSACHUSETTS, AND PETER J. LANDRY, OF PELHAM,
NEW HAMPSHIRE.

MULTIPLE-FEED CIRCULAR SPRING-NEEDLE KNITTING-MACHINE.

1,390,164.

Specification of Letters Patent.

Patented Sept. 6, 1921.

Application filed December 20, 1919. Serial No. 346,297.

To all whom it may concern:

Be it known that we, ALFRED A. ROY and PETER J. LANDRY, both citizens of the United States, residing, respectively, at 5 Lowell, in the county of Middlesex and Commonwealth of Massachusetts, and at Pelham, in the county of Hillsborough and State of New Hampshire, have invented a certain new and useful Improvement in 10 Multiple-Feed Circular Spring-Needle Knitting-Machines, of which the following is a specification.

This invention relates to multiple feed circular spring-needle knitting-machines, 15 and is a press-off preventer.

In machines of the character referred to a single head or cylinder of needles is used with, from four to seven feeds, each of which is driven by the rotation of said cylinder 20 and normally feeds or delivers a yarn to the cylinder and with the cylinder knits a course of the fabric so that a single revolution of the cylinder knits as many courses as there are feeds, and so that in one sense the 25 machine may be considered a plurality of machines, each consisting of a feed with a needle cylinder common to all of them. Now, if the yarn of any feed fails, that feed will continue to be driven by the needle 30 cylinder, the beards of the needles passing said feed will be closed, but there being no yarn under said beards the loops on the needles will be carried over the tops of the needles and the fabric will be entirely disconnected from the needles at that feed and 35 at all the subsequent feeds, constituting what is known as a "press off," the piece of fabric already knitted being then generally waste or seconds,—the cost of replacing the 40 fabric properly upon the needles being prohibitive.

The object of this invention is to throw out of action the beard-closing means of any feed upon the failure of the yarn operated 45 upon by that particular feed, by failure, meaning the breakage or exhaustion of such yarn.

In the accompanying drawing, Figure 1, is a plan of a part of the head or needle-cylinder of a circular spring-needle knitting-machine and one feed and our invention applied thereto;

Fig. 2, a side elevation of part of the head with needles, a needle-clamp and the presser-

release, its operating lever, and stand, and 55 the presser;

Fig. 3, a plan of the cover of the supporting parts of the presser-release and presser;

Fig. 4, a perspective view of the body of the case;

Fig. 5, a side elevation of the presser-release and connected parts;

Fig. 6, a plan of the same and of the presser;

Fig. 7, a right side elevation of the yarn- 65 guide and yarn-controlled lever.

The head A or needle-cylinder, Figs. 1, 2, spring-needles a, their beards a²; clamps a¹; clearing wheel B, stitch-wheel or loop-wheel C; dividing wheel D, landing-wheel E, finishing-wheel F,—these are all of any usual construction and operation;—the cylinder being rotated around its vertical axis by well-known means (not shown), and carrying the needles and rotating the above specified wheels by engagement with the needles in the usual manner.

The yarn Y is drawn from a bobbin or cone (not shown) and is directed to the stitch-wheel C by a yarn-guide c of usual form. The presser G, which closes the beards a² of the needles by pressure against said beards, is represented as a non-rotary presser, (for which the well known presser-wheel may be substituted if desired), slides 80 in a case or frame H supported on a stand consisting of a vertical hollow base I (Figs. 2, 4) and an angle-iron i, the vertical arm of which is held at the desired height by a set-screw i¹, the upper horizontal arm i² of said angle-iron entering a horizontal opening h² in said case H and being held from movement by a set-screw h¹. A cover H¹ (Fig. 3) is provided for inclosing the body portion of the case. The head of the presser G is adjustably held on the shank g¹ thereof by the set-screw g², and is forced toward the beards of the needles by a spring, represented as a spiral wire spring g³ surrounding said shank g¹ and compressed between an enlargement 95 g⁴ of said shank g¹ and a sleeve g⁵ on said shank, said sleeve being adjustable on said shank by a nut g⁶ and check-nut g⁷ turning on the threaded portion of said shank, to vary the pressure of said presser upon the 100 beards a². The sleeve g⁵ is provided with a notch g which receives one end of the locking-bar J,

A yarn-controlled lever K (Figs. 1 and 7), is represented as pivoted at k^1 on a support which may be an outward extension L of the yarn-guide c and this extension L is provided with downwardly extending spaced pins l and said lever K is provided with similar spaced pins k parallel with said pins l and so arranged that the pins on the lever normally enter the spaces between the pins on its support.

The yarn Y passed down through the yarn-guide extension L and then is bent alternately by the pins on the extension L and on the lever K into a zigzag course as shown in Fig. 1, preventing the inner end of the lever from moving to the right or outward.

When the bobbin or cone is exhausted of yarn or when the yarn breaks or slackens to such an extent as to allow the lever to swing outward into the position indicated by dotted lines in Fig. 1, the outer end of said lever K becomes disengaged from the end (the right end in Fig. 1) of the link M, which link is connected to the outer end of the release-operating lever N, pivoted at n on the bottom of the case to swing in a horizontal plane, and the outer end of said lever N is then swung outward by a spring n^1 , represented as a U-shaped spring, one end of which is connected to the outer arm of said lever N and the other end of which engages the bottom of the case H.

The other end of the release-operating lever N is provided with notches n^2 which engage pins or teeth o which project down from the under side of the segmental releasing wheel O, which turns on a vertical axis o^1 and rotates said wheel O until its curved surface o^2 of larger diameter comes against the needles below the beards of the needles by contact with which said wheel is further rotated, bringing another projection or pin o^3 from the top of said wheel against the inner arm p of the lever P pivoted at p^1 in the case H and causing the outer arm p^2 of said lever which projects through or is otherwise connected to the outer end of the locking-bar to draw said locking-bar J out of the notch g in the sleeve g^5 , allowing the presser

to be moved away from the beards of the needles by the spring Q secured to the case H at q, and pressing outward against the stud g^6 which projects from the sleeve g^5 .

After the presser is thus moved away from the needles the knitting-wheel A, B, C, D, E, of the particular feed to which the presser belongs will continue to revolve but without affecting the fabric, and the other feeds with the cylinder will continue to knit, so that the only harm done by the breaking of the yarn will be a loss of production.

The edge of the releasing-wheel O should be adapted to engage the shank of the needle and this may be accomplished by providing it with a tire o^4 of rubber, leather or similar yielding material.

We claim as our invention:

1. In a circular knitting machine, in combination, a plurality of needles, a presser, means to hold said presser in position to close said needles successively, yarn controlled means effective to withdraw said presser to inoperative position, and controlling mechanism for said latter means, said mechanism comprising a latch to hold said presser in operative position, a cam wheel rotatable by engagement with a continuously moving part of the machine, connections from said cam wheel to said latch, and yarn controlled means for advancing said cam wheel to engaging position.

2. In a circular knitting machine, in combination, a plurality of needles, a presser, means to hold said presser in position to close said needles successively, yarn controlled means effective to withdraw said presser to inoperative position, and controlling mechanism for said latter means, said mechanism comprising a latch to hold said presser in operative position, a cam wheel, connections from said cam wheel to said latch, yarn controlled means to partially rotate said cam wheel upon yarn failure, and mechanical means to further rotate said wheel to release said presser.

ALFRED A. ROY,
PETER J. LANDRY.
